UNITED STATES PATENT OFFICE

2,571,594

SWAGING MACHINE AND FEEDER
THEREFORClarence E. McKinsey, Painesville, Ohio, assignor
to General Electric Company, a corporation of
New York

Application November 3, 1945, Serial No. 626,557

4 Claims. (Cl. 78—97)

I

My invention relates in general to wire swaging apparatus, and more particularly to apparatus for automatically feeding lengths of wire endwise into the swaging head of a wire or metal swaging machine.

Certain types of lead-in wires for large sized electric incandescent lamps comprise an inner lead portion of relatively heavy, rigid wire, one end of which is formed with a hook for clamping the lamp filaments therein and the other end of which is tapered down to conform in size to the diameter of the seal wire portion of the lead-in wire which is butt-welded thereto. In forming such inner lead portions, it is customary to first form the filament clamp hook at one end of the wire and to then taper or swage the opposite end of the wire down to the required diameter by insertion into the swaging head of a conventional type wire-swaging machine.

Heretofore, the insertion of the hooked end leads into the swaging head has been performed by hand, the operator simply grasping the hook end of the lead and then moving it endwise into the aperture in the swaging head. However, such hand insertion of the leads into the swaging head, besides being a slow and tedious operation, often resulted in injury to the operator's hand due to the frequent catching of the leads in the rotating dies of the swaging head. When this occurred, the lead would be rapidly rotated or spun around in the operator's fingers with such force as to cause the hook thereon to severely cut the operator's fingers, even though a protective glove were worn by the operator.

One of the objects of the present invention, therefore, is to provide wire swaging apparatus, for swaging the end of a length of wire, which is fully automatic in operation.

Another object of my invention is to provide apparatus for automatically feeding lengths of wire endwise into and removing them from the swaging head of a wire swaging machine.

Still another object of my invention is to provide apparatus of the above mentioned type which will automatically insert the lengths of wire a predetermined distance into the swaging head.

Further objects and advantages of my invention will appear from the following description of a species thereof and from the accompanying drawing in which:

Fig. 1 is a front elevation, partly in section, of apparatus comprising my invention; Fig. 2 is a plan view of the said apparatus; Fig. 3 is a vertical section on line 3—3 of Fig. 1 but with the wire-elevating slide shown in its lowered position;

2

tion; Fig. 4 is a plan view of the plunger head and its cooperating cam plate, the plunger head being shown in its starting or wire-receiving position; and Fig. 5 is a view similar to Fig. 4 but with the plunger head shown in an advanced or wire-gripping position.

Referring to the drawings, the invention is there shown as applied to a conventional wire swaging machine such as that manufactured by the Torrington Company of Torrington, Connecticut, and comprising a swaging head 1 mounted on a table 2 and containing dies (not shown) for swaging a wire inserted endwise into an aperture 3 in the head 1. In accordance with the invention, the wires 4 to be swaged are stored in a hopper 5 mounted on the upper side of the table 2 in a position alongside the front face 6 of the swaging head 1 and below the path of movement of the wires 4 into the said head. 10 The hopper 5 is arranged to receive and hold the wires 4 in substantially parallel relation to one another and to their path of movement into the swaging head 1. In the particular case illustrated wherein the wires 4 are formed with hooks 15 7 (Figs. 4 and 5) at one end, they are loaded into the hopper 5 with their other or plain ends (i.e., the end to be swaged) facing the swaging head 1. As shown in Fig. 3, the ends 8 of the hopper 5 converge downwardly so as to guide the wires 20 4 laterally in the hopper into a position more or less directly underneath their head-inserting position.

The wires 4 in the hopper 5 are lifted one at a time out of the hopper and elevated to a position opposite and in alignment with the wire-insertion aperture 3 in the swaging head 1 by means of wire-elevating mechanism comprising a vertically reciprocating slide or elevator 9 which is guided in ways 10 in a bracket 11 fastened to and depending from the underside of the table 2. The slide 9 is held in the ways 10 of the bracket 11 by a cover plate 12 fastened to the bracket, as by screws. The upper end of the slide 9 is formed with a groove 13, of semicircular cross-section conforming to the cross-section of the wires 4, for receiving one of the wires therein. The sides of the slide 9 are rounded or tapered steeply away from the opposite side extremities of the groove 13, as indicated at 14 in Fig. 3, 35 so as to cast aside all wires other than the one picked up in the groove 13 during the upward movement of the slide through the stack of wires 4 in the hopper.

The slide 9 is normally located in a lowered position beneath the table 2 with its upper end lo-

cated below the bottom wall 15 of the hopper 5. During the operation of the machine, the slide 9 is moved vertically upward, through aligned openings 16 and 17 in the table 2 and bottom wall 15 of the hopper, to the elevated position shown in Fig. 1 wherein the wire 4 within the groove 13 in the slide is positioned opposite and in alignment with the wire-insertion aperture 3 in the swaging head 1. The said elevated position of the slide 9 is determined by the engagement of an adjustable stop screw 18 with a stop lug 19 extending from the lower end of the slide support bracket 11. As shown in Fig. 1, both the slide 9 and the hopper opening 17 therefor are made of shorter extent than the length of the wires 4 and are centrally located relatively to the hopper sides so that the wires 4 overlying the opening 17 are supported at their opposite ends by the bottom wall 15 of the hopper and are thus prevented from falling through the opening 17 when the slide is in its lowered position whence they would become jammed between the slide and the underside of the hopper bottom wall 15 upon subsequent upward movement of the slide.

The vertical reciprocating movement of the slide 9 is imparted thereto by a rocker arm or lever comprising arms 20, 21 mounted on a shaft 22 which is journaled in a bracket 23 fastened to and depending from the underside of the table 2. The swinging end of arm 20 is pivotally connected to the slide 9 by link 24 while the swinging end of arm 21 is pivotally connected by a connecting rod 25 to one arm 26 of a bell crank lever 27 pivoted on a shaft 28 extending from an upstanding bracket 29 fastened to the upper side of the table 2. The connecting rod 25 moves through an elongated opening 30 in the table 2 which opening is also arranged to receive the arm 26 of the bell crank lever 27 during its oscillating movement. The other arm 31 of the bell crank lever 27 is provided with a roller 32 which rides on the periphery or cam edge 33 of a plate cam 34 mounted on a cam shaft 35 journaled in the bracket 29. The cam shaft 35 is rotated at the desired operating speed by means of an electric motor-driven speed reducer 36 which is mounted on the upper side of the table 2 and which drives the cam shaft through a gear train comprising spur gears 37, 38, 39 and 40. Gear 37 is mounted on the shaft 41 of the speed reducer and meshes with gear 38 mounted on a stud shaft 42 journaled in an upstanding bracket 43 fastened to the upper side of the table 2. Gear 39 is also mounted on the shaft 42 and meshes with the gear 40 which is mounted on the cam shaft 29. Tension coil springs 44 and 45, respectively connected at one end to the rocker arm 20 and to the bell crank lever arm 31, tend to hold the roller 32 on the bell crank lever in continuous engagement with the periphery 33 of the cam 34 and thus pull the slide 9 upwardly to its elevated position with the stop screw 18 in engagement with the stop lug 19. Spring 45 is connected at its other end to a spring post 46 extending from bracket 29 while spring 44 is connected at its other end to a suitable stationary part of the machine, such as platform 47 located above the table 2. The spring 44 extends through a suitable opening 48 provided therefor in the table 2.

Upon being carried by the slide 9 from the hopper 5 to its elevated position opposite the aperture 3 in the swaging head 1, the wire 4 is then advanced endwise into the swaging head by a wire-inserting mechanism to thereby effect the

swaging of the forward end of the wire. The said wire-inserting mechanism comprises a horizontally reciprocating carriage or push rod 49 carrying a head assembly or chucking means 50 at its forward end for engaging and firmly gripping the hooked end portion 7 of the elevated wire 4. The push rod assembly or carriage 49 is slidably mounted in bearings 51 on an upstanding bracket 52 fastened to the upper side of the platform 47 which is supported at its opposite ends on the bracket 29 and the swaging head 1.

As shown more particularly in Figs. 4 and 5, the push rod head or chucking means 50 comprises a block-shaped member 53 non-rotatively fastened to the front end of the push rod, as by a set screw, and formed with a cone-shaped recess 54 in its front face providing a seat for the hooked end 7 of the wire 4. The push rod head 50 carries a pair of pivoted jaws 55, 55 provided with wire-receiving V-notches 56 (Fig. 4) in their gripping faces for gripping and holding the wire firmly a short distance from its hooked end 7 during the insertion of the wire into and its removal from the swaging head 1. The jaws 55 are received within and pivoted in horizontal slots 57 in the opposite sides of the block 53, and they are mounted on vertical shafts 58, 58 which are carried by the block 53 and project downwardly beyond the underside thereof. Jaw operating arms 59, 59 provided with rollers 60, 60 are secured to the projecting lower ends of the jaw shafts 58. A tension coil spring 61, connected between posts 62 on the two jaws 55, tends to pivot and maintain the jaws in their closed or wire-gripping position as shown in Fig. 5.

When the push rod or carriage 49 is in its retracted position, the jaws 55 are held in open or separated position (Fig. 4), to receive the wire 4 therebetween, by the engagement of the rollers 60 on arms 59 with forwardly diverging cam surfaces 63 on a cam plate 64 carried by a bracket 65 fastened to the upper side of the platform 47. During the subsequent advance movement of the push rod 49 towards the swaging head 1, the hooked end 7 of the elevated wire 4 is received and seated in the recess 54 in the block 53 and the divergent cam surfaces 63 allow the rollers 60 to separate, thus permitting the spring 61 to pivot the jaws 55 to close them against the wire 4. The engagement of the hooked end 7 of the wire 4 within the seat 54 together with its engagement by the jaws 55 thus serves to hold the wire firmly in position. As soon as the jaws 55 grip the wire 4 during the advance movement of the push rod 49, the slide 9 is then lowered out of the way of the advancing push rod 50 by the rise of the slide operating cam 34.

The horizontally reciprocating movement of the push rod 49, to advance the wire 4 into and retract it from the swaging head 1, is imparted thereto by a more or less vertically extending lever 66 pivoted at its lower end on the shaft 28 and connected adjacent its other end, by link 67, to the rear end of the push rod. At a point intermediate its length, the lever 66 carries a roller 68 which rides on the periphery or cam edge 69 of a plate cam 70 mounted on the cam shaft 35. The roller 68 is continuously held against the cam surface 69 by the pull of a freely suspended weight 71 carried by a steel tape 72 which is drawn over a pair of pulleys 73, 74 and is connected at its other end by link 75 to the upper end of the lever 66. The pulleys 73, 74 are rotatably mounted on upstanding brackets 76, 77 mounted respectively on the table 2 and the

platform 47. The use of a freely suspended weight 71 rather than a coil spring to advance the push rod 49 so as to insert the wire 4 endwise into the swaging head 1 is preferred for the reason that such weight 71 will not vibrate, as a coil spring would, under the action of the swaging dies in the swaging head. The use of the weight 71 therefore insures that the wire 4 will not vibrate back and forth during its insertion into the swaging head 1, a condition which would otherwise result in improper swaging of the wire and corresponding loss of concentricity.

The forward movement of the push rod 49, and therefore the amount of advance movement of the wire 4 endwise into the swaging head 1, is limited by the engagement of the lever 66 with an adjustable stop screw 78 (Fig. 1) carried by an arm 79 fastened to the bracket 29. By adjusting the position of the stop screw 78, the extent of swaging of the wire 4 back from its forward end may be varied. To give a ready indication, for a given setting of the stop screw 78, of the amount of forward movement of the push rod 49 and therefore the extent of swaging of the wire 4, the upper end of the lever 66 is provided with a pointer 80 which moves across or scans a horizontally disposed bar 81 provided with suitable graduations 82. The bar 81 is supported at its opposite ends on the pulley support brackets 76, 77.

After the wire 4 has been inserted the full distance into the swaging head 1 to thereby complete the swaging of the wire, the push rod 49 is retracted by the rise on the cam 70 to thereby withdraw the wire from the swaging head. Simultaneously with the retraction of the push rod 49, the wire-elevating slide 9 begins its upward stroke by reason of the drop on the cam 34 and the pulling action of the coil springs 44, 45. During the last portion of the retracting movement of the push rod 49, the rollers 60 on the jaw pivoting arms 59 strike against and ride along the converging cam surfaces 63 of the cam plate 64, causing the jaws 55 to open and thus release the swaged wire 4 which is then free to drop. The released wire 4 falls onto a rearwardly declined movable chute or deflector plate 83 which guides the wire into a similarly declined stationary chute 84 the receiving end of which is located just to the rear side of the slide 9 when the latter is in its elevated position so that the said chute is out of the path of vertical movement of the slide. Upon dropping into the chute 84, the wire 4 then slides down the said chute into a collecting box 85 mounted on the table 2 beneath the discharge end of the chute.

The deflector plate 83 is fastened to a swinging arm 86 so that it may be swung out of the way of the wire-carrying slide 9, during the upward movement of the latter, to thereby enable the slide to elevate the wire 4 carried thereby to its position opposite the aperture 3 in the swaging head 1. The arm 86 is pivoted on a pin 87 projecting forwardly from the push rod head block 53, and it carries a stop pin 88 which engages the upper surface of the block 53 to thereby determine the pivotal wire-deflecting position of the arm 86 and deflector plate 83. The said arm 86 and plate 83 are normally held in their wire-deflecting position (shown in full lines in Fig. 3) by the pressure of a plate spring 89 which is fastened to the upper side of the block 53 and bears downwardly against the stop pin 88 on the arm 86. The deflector plate 83 is swung out of the path of upward movement of the slide 9 by

the slide itself, the free end of the deflector plate 83 being bent downwardly and forwardly for this purpose to provide a steeply inclined tongue portion 90 which is engaged by the rounded upper end portion 14 of the slide 9 to thereby pivot the said plate 83 and its support arm 86 upwardly, against the resistance of the plate spring 89, until the slide is free to ride over the bend 91 in the deflector plate 83. As the upper end of the slide 9 passes down beyond the bend 91 in the deflector plate 83 on the ensuing downward stroke of the slide, the spring 89 then pivots and returns the arm 86 and associated deflector plate 83 to their wire-receiving position once again.

What I claim as new and desire to secure by Letters Patent of the United States is:

1. In combination with a wire-swaging machine of the type having a head adapted to taper down an end of a length of wire, apparatus for feeding the lengths of wire into the work-receiving aperture of the swaging machine head comprising a wire-storage hopper mounted adjacent the swaging head, transfer means for picking up the wires in said hopper one at a time and transferring them to a horizontally extending position opposite and longitudinally aligned with the said aperture, a carriage horizontally reciprocable towards and away from the swaging head to carry the positioned wire into and out of the swaging head aperture, said carriage being provided with chucking means arranged to grip and hold the said positioned wire in its said longitudinally aligned relation with said aperture during the reciprocating movement of the carriage, and means for actuating the transfer means and carriage in proper time relation, said actuating means comprising a cam, a follower riding on said cam and connected to the carriage to reciprocate the same, and a freely suspended weight connected to said follower for holding it in engagement with the cam and advancing the carriage towards the swaging head to press the wire carried thereby into the swaging head with uniform force.

2. Apparatus for feeding lengths of wire into the work-receiving aperture of a swaging machine head of the type having a head adapted to taper down the inserted end of the wire, comprising a hopper for holding a supply of the wires, an elevator movable upwardly through the hopper to pick up one of the wires therein and elevate it into a horizontally extending position opposite and longitudinally aligned with the said aperture, a carriage horizontally reciprocable towards and away from the swaging head to carry the positioned wire into and out of the swaging head aperture, said carriage being provided with chucking means arranged to grip and hold solely by itself the said positioned wire in longitudinally aligned relation to said aperture during the reciprocating movement of the carriage, and means for actuating the elevator and carriage in proper time relation to raise the elevator during retraction of the carriage and to lower the elevator during the advance movement of, but only after gripping of the positioned wire by the holder means on the carriage, said actuating means comprising a freely suspended weight operatively connected with said carriage to advance it toward the swaging head and press the wire carried thereby into the swaging head with uniform force.

3. Apparatus for feeding lengths of wire into the work-receiving aperture of a swaging machine head of the type having a head adapted to taper down the inserted end of the wire, comprising

ing a hopper for holding a supply of the wires, an elevator movable upwardly through the hopper to pick up one of the wires therein and elevate it into a horizontally extending position opposite and longitudinally aligned with the said aperture, a carriage horizontally reciprocable towards and away from the swaging head to carry the positioned wire into and out of the swaging head aperture, said carriage being provided with chucking means including opposed jaws for gripping and holding solely by itself the said positioned wire in longitudinally aligned relation to said aperture during the reciprocating movement of the carriage, means for actuating the elevator and carriage in proper time relation to raise the elevator during retraction of the carriage and to lower the elevator during the advance movement of the carriage, said actuating means comprising a freely suspended weight operatively connected with said carriage to advance it toward the swaging head and press the wire carried thereby into the swaging head with uniform force, means for opening said jaws to release the swaged wire upon retraction from the said aperture, a wire-receiving chute located to one side of said elevator, and a deflector mounted on said carriage and

arranged to receive and guide into said chute the swaged wire as it is released by and drops from the jaws, said deflector being movable out of the path of said elevator during the upward stroke of the latter.

4. Apparatus of the character set forth in claim 3 wherein the said deflector is pivotally mounted on the carriage and is spring-held in a normal wire-deflecting position, said deflector having a cam surface engageable by the elevator during the upward stroke of the latter to thereby pivot the deflector out of the path of movement of the elevator.
